PHOTOGRAPHIC CLIP

Anthony Ludwig, Falls Church, Va.

Application November 28, 1950, Serial No. 197,886

8 Claims. (Cl. 24—259)

1

This invention relates to clips and particularly to clips for long or short strips which have to be processed in liquids, such as photographic films.

In the making of photographic negatives, the films are passed successively from one tank containing a processing solution to another tank containing another processing solution, after which the films are washed and dried.

In the processing of ordinary black and white 10 negatives, the films are first attached to clips which are carried by the developing machine, which places the films in a tank containing a developing solution. After the film is developed, it is usually placed in a so-called "short stop" 15 solution which arrests, at once, all action of any developer solution which may have remained on the film. After treatment in the "short stop" solution, the film is removed and placed in a hypo solution. This hypo solution removes all 20 of the light-sensitive portion of the emulsion on the film body which has not been affected by the light exposure. This completes the processing except for washing and drying of the negative.

After the hypo treatment, the negative is removed from the hypo solution and placed in a water bath. In some laboratories it is customary to use two hypo baths—first a weaker bath and then a stronger bath. The negative, before passing to the dryer, may be put through one, two, 30 or more water baths to be sure that all of the hypo has been removed.

In removing a clip with its attached negative from one solution to go into another, it is obvious that it is advantageous if the clip is so shaped 35 as to cause practically all of the solution to run off as the clip and its negative emerge from the surface of the solution. This is important because (1) there is a minimum loss of solution and (2) there is a minimum contamination of 40 the next solution. And when the negative has finished being washed, there is less water to be removed by evaporation.

Also, in developing and washing photographic films, considerable trouble has been encountered due to other causes. The clips have collected and held water until after the films were dried and when disturbed, have given up the water to be deposited on the films. This causes the emulsion to be distorted when dried the second time 45 and when printed, transmits the appearance of a drop of water. To avoid this retention of the water on the clips to be later, perhaps accidentally, deposited on the film, some laboratories have installed an additional bath with what is

2

called a "wetting agent." This bath may contain "aerosol" or some similar agent whose function it is to destroy the surface tension of the water, promoting its draining from the clips. 5 This extra bath would be useless if the water drained properly from the clips.

With the clips in use at the present time, for example in photographic development, there has been found to be a definite tendency for the clips to hold on their surfaces, the liquids such as chemicals and water, for a longer time than desirable after having been removed from the chemical or water bath.

In the case of the chemicals, as already pointed out, too much of the liquid chemical is drawn out on the surface of the clip, thus wasting the chemical and unnecessarily contaminating the next bath into which the film and its clip may be inserted. In the case of the water, too much of the water adheres to the clip after passing through the final water bath. This often results in the retention of much water on the clip after the film is thoroughly dried. The result of such a condition is that upon removal of the film and clip from the drying rack, the water retained on the clip is disturbed and runs onto the film. This water rewets the film and may result in (1) streaks on the film or (2) damage to the film, made possible by contact after being softened by the water and (3) tear drop marks as already pointed out.

In any event, this surplus chemical solution or water is undesirable on either the clip or its support.

Another difficulty in the use of clips in the processing of photographic films has been the fact that it is as necessary, if not more necessary, that the clip with its weight at the bottom of the film shed its liquid as efficiently as the clip at the top of the depending film. This is for the reasons (1) that all of the liquid at the top runs to the bottom and also (2) that the normal and conventional location of the spring bow of the conventional clip at the lower end away from the gripping jaws of the clip tend to furnish a collecting place for the liquid. It is obvious that the film must be held in a steady position to prevent it from contacting with other films and to prevent it from curling.

The primary object of this invention is the provision of an improved clip for use in processing photographic films and the like.

Another object of the invention is the provision of an improved photographic clip wherein liquids from the respective processing tanks will

be quickly discharged from the surfaces of the clips as they are lifted from their processing liquids, thus minimizing the loss of the liquid from the tank out of which the clip and film are lifted and also reducing the contamination of the liquid of the tank into which the film with its clip is to be placed.

A further object of the invention is the provision of an improved photographic clip wherein there is provision for efficient discharge of the liquid from its surface when the clip is used at the bottom of the film, with its weight to hold the film in a vertical position to prevent curling during the processing.

Still another object of the invention is the provision of a photographic clip wherein its parts are so shaped that with the clip used as a bottom clip, and the clip with its film are withdrawn from a processing liquid, the liquid on the surface of the clip will be at once conducted to portions of the clip having no substantial horizontal area and quickly discharged therefrom.

Still another object of the invention is the provision of a photographic clip for use as a bottom clip having an arch-shape bow having inverted U-shaped cross sections whereby the liquid of a processing bath is conducted to lower portions of the clip which have discharging points of substantially no horizontal area.

Still another object of the invention is the provision of a photographic clip for use as a top or bottom clip which has an arch-shape bow having liquid-shedding inverted U-shape portions whereby the liquid of a processing bath is conducted to lower portions of the clip which have discharging points of substantially no horizontal area, regardless of which end of the clip is uppermost.

Still another object of the invention is the provision of a photographic clip for use with its gripping means at the top, and in this position having its walls substantially out of horizontal planes and being free of pockets or other portions which might retain liquid and prevent its discharge from the clip.

A still further object of the invention is the provision of a photographic clip for the bottom of films being processed wherein the walls are spaced apart in such a manner as to prevent liquid from lodging between two surfaces by surface tension.

Another and further object of the invention is the provision of a photographic clip wherein when the gripping means are at the top as for use as a bottom clip, the bow section will be of an inverted U-shape and will guide the liquid to surfaces out of a horizontal plane and with lower edges out of the horizontal and having the lowest points of substantially no horizontal area to facilitate the discharge of the liquid from the clip.

Another and still further object of the invention is the provision of a photographic clip having an inverted bow section and having the surfaces below the bow section in substantially vertical planes with lower edges at substantial angles to the horizontal with the lowest points having no substantial horizontal area.

Another and still further object of the invention is the provision of a photographic clip for use either with the gripping means at the top or bottom and wherein in either position the bow portion will have an inverted U-shaped cross section for conducting the liquid to lower portions of the clip.

Another and further object of the invention is the provision of a photographic clip for use at the bottom of a film being processed and wherein the gripping is at points with the film free from other contacts and wherein the portions below the bow section are substantially in vertical planes and free from other surfaces and with their lowest points having no substantial horizontal area.

Another and still further object of the invention is the provision of a clip whose jaws will be so formed that while the teeth will grip the film firmly, they will not perforate the film, which would weaken it and make it less resistant to tearing and allowing the clip to be pulled from the film.

Another and further object of the invention is the provision of a clip whose jaws are so formed that they cover the least possible portion of the film so that they do not retard free circulation of air or interrupt heat rays or infrared rays to the film surfaces, thus making possible the quick drying of the portion of the film near the jaws of the clip. This provision is very important since clips which enclose a portion of the film will prevent the drying at the point where held and if these ends are not carefully removed, they are liable to touch and adhere to good negative portions of adjacent films. In such a case, the adjacent film is completely ruined when the two are pulled apart.

Other and further objects of the invention will be apparent from a reading of the complete specification.

Referring to the drawing wherein I have illustrated different forms of my invention,

Fig. 1 is a front view of my preferred form of clip used as a bottom clip for a film processing.

Fig. 2 is a view similar to Fig. 1 but showing the same type of clip as a top clip, partly in section.

Fig. 3 is a side view of the structure shown in Fig. 1.

Fig. 4 is a top plan view of the structure shown in Fig. 2, being the same showing of a bottom view of the structure shown in Figs. 1 and 3.

Fig. 5 is a detail view of a modified form of one of the gripping devices.

Fig. 6 is a pattern of the modified form of spring means shown in Fig. 5.

Fig. 7 is a view at 90° to the showing in Fig. 5 but with the complementary gripping member in coactive relation.

Fig. 8 is a front view of an adaptation of the clip shown in my co-pending application, Serial No. 197,885, filed on November 28, 1950, showing a construction for use as a bottom clip. Reference is also made to my application copending herewith and now abandoned, Serial No. 661,099, filed April 10, 1946.

Fig. 9 is a side view of the structure shown in Fig. 8.

Fig. 10 is a top plan view of the structure shown in Figs. 8 and 9.

Fig. 11 is a pattern of the structure of Figs. 8, 9 and 10.

Fig. 12 is a combination of a modification of the bow portion of Figs. 1 to 4, the remaining portions being constructed as Figs. 8, 9 and 10.

Fig. 13 is a side view of Fig. 12, parts being broken away for clearness.

Fig. 14 is an enlarged detail sectional view on the line 14—14 of Fig. 13.

Fig. 15 is a detail showing of a modified form of gripping tooth arm.

The same reference characters are used to designate the same and similar parts throughout the specification and drawing.

In carrying out the spirit of this invention, it has been a purpose generally to provide a photographic clip which will quickly get rid of liquids from its surface and which may be used as either a top or bottom clip with equal success.

Referring to the structure of Figs. 1 to 4, I have provided a bow shaped body portion with front and rear leg portions 20a and 20b and an end portion 20c which I term the bow. The front leg portion 20a has its sides notched in between the bow end and the clip end as at 20d. Attached to the edges of the rear leg portion 20b are folded portions 20e which carry gripping portions as will be presently set forth. These folded portions 20e are preferably provided with ribs 20f to stiffen the folded portions and assure the registration of the gripping teeth. It will be observed that the folded portions 20e normally clear the sides of the front portion 20a and also that their surfaces are substantially in vertical planes with their top and bottom edges out of horizontal planes, regardless of the use as a top clip or as a bottom clip.

At the extended ends of the folded portions 20e, there are provided teeth 20g which with complementary members of the front portion, form the gripping means of the clip. These teeth 20g are provided with top and bottom edges which are out of the horizontal plane and which will not, therefore hold water. When used as a bottom clip, the liquid will at once be conducted to the film where it will be carried to the bottom end for discharge. But when used as a top clip, these edges of the teeth illustrated in Fig. 3 will conduct the liquid away from the film to points of discharge as will later be more fully explained. The extreme ends of the folded portions 20e are provided with discharge ends 20h which have little or no horizontal area and for practical purposes are points. Referring particularly to Fig. 3, it will be observed that the outer edge of the folded portion 20e has a curved contacting portion 20q to permit the bearing of the film F as it is received by the clip, as will be described.

At the end of the front portion 20a, opposite the bow 20c, are two extensions 20k which may be provided with strengthening ribs 20m. These extensions have non-horizontal edges to conduct liquid toward the lower end of the clip, whether the clip is being used as a top or a bottom clip. Opposite to and in positions to coact with the teeth 20g are ribs 20n, on the extensions 20m, which are slightly longer than the width of the teeth 20g. They are not, however, sufficiently long to interfere with the draining of the liquid which is of prime consideration. They do, however, provide for proper registration with the teeth 20g, even though, from rough handling, the teeth become slightly bent. At the far tip end from the bow 20c, the extensions 20k terminate in ends 20p which have practically no horizontal area and for practical purposes are points. When the clip is being used as a top clip, as illustrated in Fig. 2, these points conduct the liquid from the clip, it being well known that a liquid drop has very little tendency to remain on a point. The end 20p is bent away from the position occupied by the film F, as shown in Fig. 3 and with the outer inclined edge of the outer tooth 20g, form a guide means to conduct the film into position between the teeth 20g and the ribs 20n. When the film F is to be inserted, the two body portions 20a and 20b

are pressed toward each other. This separates the teeth 20g from the ribs 20n and opens a space for the film. The film, as it is inserted, engages the edge 20q, as shown in Fig. 3. The fingers of the operator now release the clip and the resiliency of the clip, causes the teeth 20g to impinge the surface of the film and bind it against the ribs 20n. A weight 21 is secured to the inner side of the rear portion 20b by any suitable means 10 to give weight to the clip when used as a bottom clip. The weight 21 is of a shape and is applied in such a manner that the liquid will be conducted downwardly and away, without regard to which end of the clip is uppermost. Such a shape and position is illustrated in Figs. 1 to 4.

The double arch construction which permits of efficient use of this clip as a bottom clip or as a top clip, will now be described. At the bow end of the clip, there is a space 20r which has been cut away to destroy the pocket which would otherwise be present to collect liquid. At the outer sides of the bow, there is a secondary arch 20s impressed into the bow which, when the clip is used as a top clip as shown on Fig. 2, conducts 25 the liquid to the substantially vertical outer surfaces of the front and rear portions 20a and 20b, respectively.

When the clip is used as a bottom clip as shown in Fig. 1, the liquid is conducted to each 30 side of this arch, the liquid from each arch surface being conducted off, half to the outer side of the bow 20c and the other half through the opening 20r. To assist this discharge of the last drop of liquid, there may be provided slight points 35 20t at the lowest part of the arch as clearly indicated at the very bottom of Fig. 3.

A modification of the end portions 20k and their ribs 20n will now be described. Substituted for the extension 20k are the extensions 20u each 40 of which is provided with one or more bent tabs 20w which tabs are shown in their pattern in Fig. 6 and bent into operative shape in Figs. 5 and 7. It is to be noted that these tabs are very slightly inclined to cause the liquid to be quickly conducted away but sufficiently close to the normal 45 position of the teeth 20g that any slight bending of the teeth due to careless handling will not affect the efficient operation of the clip.

A modified form of the invention will now be 50 described. In this form as with the other, a clip is provided which will operate as a bottom clip, one adaptation being of a construction which will operate either as a bottom or a top clip.

Referring now particularly to Figs. 8 to 11, the 55 bow has been designated by the numeral 120c having two leg portions extending therefrom which are designated as 120a and 120b, respectively. Extending from the leg portion 120a are two arms 120d which carry the teeth 120e which are a part 60 of the teeth gripping means. These teeth, as the others previously described, are provided with non-horizontal edges so that there will be no tendency for the edges of the teeth to hold liquid. The arms 120d are provided with suitable stiffening ribs 120x which have a tendency to resist 65 rough or careless treatment on the part of the operator. At the end of the arm 120d is an inclined edge 120f which terminates in a point 120g which point acts to quickly discharge liquid. The edges 120f serve, with a complementary surface on 70 each of the other arms, to act as guiding means for the insertion of the film to be processed.

Extending from the end 120b are the arms 120h which when bent to shape as shown in Figs. 9 75 and 10, act complementary to the arms 120d and

carry the teeth $120k$ for coaction with the teeth $120e$ already described. A rib $120m$ is provided on each arm $120h$ for stiffening these arms against bending and rough use.

The arms $120h$ may be provided, if found to be desirable, with stop arms $120n$ having bent stops $120p$ to rest on the outside of the portion $120a$, to provide especially against the teeth $120e$ and $120k$ slipping past one another in case they become bent.

Referring to Figs. 12, 13 and 14, the parts $228a$, $220b$, $220d$, $220e$, $220f$, $220g$, $220h$, $220k$, $220m$, $220n$, and $220p$ are similarly constructed to and perform similar functions to the corresponding parts $120a$, $120b$, $120d$, $120e$, $120f$, $120g$, $120h$, $120k$, $120m$, $120n$ and $120p$ already described.

The bow section $220c$ is constructed similar to the bow section $20c$ described in connection with the form of the invention illustrated in Figs. 1 to 4.

In Figs. 12, 13 and 14, the parts $220c$, $220r$ $220s$ and $220t$ are similar to and perform the same functions as the parts $20c$, $20r$, $20s$, and $20t$ and for this reason, will not be further described.

In the forms of the invention illustrated in Figs. 8 to 10 and Figs. 12 to 14, the weights 21 and 221 are similarly constructed to and perform the same function as the weight 21 already described for the form illustrated in Figs. 1 to 4.

Fig. 15 is a detail view of a form of teeth supporting arm similar to the arms $120h$ and $220h$ but with the gripping means corresponding to the construction shown in Figs. 5, 6 and 7. The arm $339h$ corresponds to the arms $120h$ and $220h$, with a rib $320k$ corresponding to the ribs $120k$ and $220k$. The tabs $320w$ correspond to the tabs $20w$ of Fig. 6.

These clips may be made of metal, plastic or any other suitable material.

The illustration of the clip in Figs. 8 to 10 shows the clip thicker than might be desirable in actual practice. This has been shown in this manner in the interest of clearness.

While modifications have been shown and described in detail, it is to be understood that the disclosures are merely illustrative and that modifications and changes may be made without departing from the spirit of the invention and within its scope as claimed.

Having described my invention, what I claim is:

1. A mounting clip for film processing having a generally U-shape spring body member, the bend of the U-shape portion being provided with legs, the two legs having opposed coacting film-gripping lateral projections having substantially point-contact with and for holding the film, and film-contacting and steady means on the clip and spaced from the said film-gripping projections laterally, and in position to coact with the film-gripping projections to hold the film in a steady position with relation to the body of the clip, the ends of the legs of the clip distant from the U-shape bend, including the gripping projections and the contacting means, terminating substantially in downwardly directed points at the lower extremities of the legs, all surface portions and edges of the clip from the U-shape bend to the said points extending downwardly and sloping to said downwardly directed points, thereby forming a continuous downwardly extending drainage surface to conduct the liquid in an uninterrupted progressive flow from all parts of the clip surface to the said points and thence from the clip, the drainage surface being

spaced from and positioned with relation to the other parts of the clip and from and relative to the film position as to promote the free passage of liquid during drainage.

2. A mounting clip for film processing having a generally U-shape spring body member, the bend of the U-shape portion being provided with two legs, each of the two legs having two opposed film-gripping lateral projections having substantially point-contact with the film, the gripping projections of one leg being opposite the gripping projections of the other leg and in position to form two coacting pairs of film-gripping projections, each of the pairs of gripping projections being a distance from the other pair to form a contacting steady means to hold the film in a steady position with relation to the body of the clip, the ends of the legs of the clip distant from the U-shape bend, and including the gripping projections, terminating substantially in downwardly directed points at the lowermost extremities of the legs, all surface portions and edges of the clip from the U-shape bend to the said points extending downwardly and sloping to said downwardly directed points, thereby forming a continuous downwardly extending drainage surface to conduct the liquid in an uninterrupted progressive flow from all parts of the clip surface to the said points and thence from the clip, the drainage surface being spaced from and positioned with relation to other parts of the clip and from and relative to the film position as to promote the free passage of liquid during drainage.
3. A mounting clip for film processing having a generally U-shape spring body member, the bend of the U-shape portion being provided with legs, each leg having a film-gripping lateral projection opposing and coacting with the projection of the other leg to grip and hold the film, and having substantially point-contact with the film, and film-contacting and steady means on the clip and spaced from the said film-gripping projections and in position to coact with the film-gripping projections to hold the film in a steady position with relation to the body of the clip, the upper and lower extremities of the clip terminating substantially in outwardly upwardly and downwardly directed points at the outermost extremities of the bend and legs, all surface portions and edges of the clip from the top outwardly directed points to the bottom downwardly directed points extending substantially downwardly and sloping to said downwardly directed points, thereby forming a continuously downwardly extending drainage surface to conduct liquid in an uninterrupted progressive flow from all parts of the clip surface from and below the top points to the bottom points and thence from the clip, regardless of which end of the clip is at the top, the drainage surface being spaced from and positioned with relation to the other parts of the clip and from and relative to the film position as to promote the free passage of liquid during the draining.
4. A mounting clip for processing film having a generally U-shape spring body member, the bend of the U-shape portion having legs, each leg having a film-gripping lateral projection opposing and coacting with the film-gripping projection of the other leg to grip and hold the film and clip together, the projections having substantially point-contact with the film, the U-shape portion having an inverted U-shape cross section with the main body of the clip hung with

its loop member in inverted-U position and having an upright U-shape cross section taken in a substantially vertical plane at substantially 90° from said inverted-U cross section, with the clip in the same said position, the upper and lower extremities of the clip terminating substantially in outwardly upwardly and downwardly directed points, respectively, the successive adjacent surface portions and edges of the clip from the top points to the bottom points extending substantially downwardly, and sloping from the upwardly directed points to said downwardly directed points, thereby forming a continuously downwardly extending drainage surface to conduct liquid in an uninterrupted progressive flow from all parts of the clip surface from and below the said top points to the said bottom points and thence from the clip, regardless of which end of the clip is uppermost, the drainage surface being spaced from and positioned with relation to other parts of the clip and from and relative to the film position as to promote free passage of the liquid during the draining.

5. A construction as set forth in claim 1 and having the surface portions of the clip adjacent the points of gripping of the gripping projections at such angles and distances sufficient to promote free circulation of air between the coacting gripping projections adjacent the gripping points and between the gripping points and the film when in place.

6. A construction as set forth in claim 1 and having a leg portion provided with a bend extending to the far side of the other leg, with its gripping projection substantially opposite the gripping projection portion of the other leg.

7. A construction as set forth in claim 1 and having the gripping points at which the gripping

action of the gripping projections takes place, of a non-piercing shape so that the gelatine of the film will be gripped without piercing the film.

8. A construction as set forth in claim 1 and having film-gripping projections in spaced pairs, the coacting projections on opposite sides of the film position being nearly but not exactly opposite the respective corresponding and coacting projections.
